SECTIONAL AND PORTABLE BOAT
STRUCTURE

William J. Evert, Burbank, Calif.

Application March 8, 1949, Serial No. 80,143

3 Claims. (Cl. 9—2)

1

This invention relates to a boat and particularly pertains to a sectional and portable boat structure.

Various types of boats have been made which have been portable, and some of them have been sectional. They have for the most part been impractical and flimsy in construction. It is desirable to provide a light weight boat structure for civilian and military operations, and it is the principal object of the present invention to provide a boat which is made in rigid strong sections, each of which is light in weight, and which sections may be easily locked together to form a boat having forward and rear sections, and, if desired, intermediate sections to lengthen the boat.

The present invention contemplates the provision of a portable floating craft, which comprises a plurality of elements adapted to be handled separately and to be assembled easily so that they may assume the positions and function of the fore and aft portions of a boat, and when desired with supplemental center portions.

The invention is illustrated by way of example in the accompanying drawing in which:

Figure 1 is a view in plan showing an assembled boat, such as a row-boat or motor boat, in which the fore and aft sections are secured together.

Fig. 2 is a view in side elevation showing the structure as indicated in Fig. 1.

Fig. 3 is a view in plan and diagram indicating the manner in which a plurality or supplemental sections may be interposed between the forward and rearward portions of the boat to increase the capacity and length of the structure.

Fig. 4 is a view in vertical section as seen on the line 4—4 of Fig. 1, showing the manner in which the fore and aft elements of the boat are joined.

Fig. 5 is a view in longitudinal vertical section as seen on the line 5—5 of Fig. 1 and shows the interlocking elements of the boat as when separated.

Fig. 6 is a side view of the bolt for locking the sections together.

Referring more particularly to the drawing, 10 indicates the forward section of the boat and 11 indicates the rearward section of the boat. The forward section is formed by a hull wall 12 which terminates in a transverse bulkhead 13. The bulkhead 13 is formed integral with a horizontal hull bottom 14, and seat 15, the latter also being integral with the hull wall 12. At the bow, a seat 16 is formed integral with the hull

wall 12. Vertical ribs 17 are cast integral with hull wall 12 and bottom 14 to strengthen the boat.

Formed integral with the bulkheads 13 are bosses 18 each of which is a central opening 19 terminating in upper and lower recesses 19'. There are two such bosses disposed near the sides of the hull. The longitudinal openings 19 in the bosses 18 are adapted to accommodate king bolts 20. These bolts are formed at their lower ends with a square portion 21. The lower ends of the portions 21 are inclined so that they will conform to the outer contour of the hull 12. The upper ends of the king bolts are threaded at 23 and receive a nut 24 which is forked to accommodate a handle 25. The handles 25 are pivoted at 26 to the fork of the nut 24. Each of the handles 23 carries a locking plunger 27 which is forced yieldably into an opening 28 by a spring 29.

20 The rearward section 11 of the boat includes hull walls 12' which are joined at the stern by a wall 30 and at their forward ends by a bulkhead 31. This bulkhead extends transversely of the hull and is formed integral with a horizontal bottom 14' and seat 15'. The walls 12' and 30 are formed integral with a seat 16'. Reinforcing ribs 17' are formed integral with the wall 12' and bottom 14' to strengthen the hull structure. Extending horizontally from upper and lower edges of bulkhead 31 are bosses 32 and 33. The boss 33 is formed with a bore 22 which is adapted to receive the portion 21 of the bolt 20. When sections 11 and 12 are juxtaposed as shown in Figs. 1 and 2, the bolt 20 extends upwardly through longitudinally aligned bores 34 and 35 which are formed through the bosses 32 and 33. At the upper end of the bore 34 there is a counterbore 36 which receives the nut 24. The section 11 is reinforced by vertical webs A formed integral with bulkhead 31 and seat 15' in the longitudinal planes of the bosses 32 and 33.

It will be obvious that it may be desirable to assemble the boat structure by using one or more sections 37. These may be inserted between the forward and rearward sections 10 and 11 to provide additional length or capacity for the boat. The manner in which the sections 10, 11 and 37 are assembled is the same as that for sections 10 and 11 above described.

45 In operation of the present invention the boat sections are constructed as shown in the drawing so that the portions 10 and 11 may be assembled as indicated in Figs. 1 and 2. When this is accomplished the bolts 20 are inserted through the openings 19 of the members 18 as well as

through the bores 34 and 35 of the bosses 32 and 33. When it is desired to fasten the boat structure in its assembled position the nuts 24 are screwed onto the threads 23 and the handles 25 are used to apply torque to the nuts. As the nuts are tightened the square portions 21 are drawn upwardly and then the handles 25 are swung downwardly from their dotted line positions to their horizontal positions. At this time the plungers 27 will extend downwardly into the openings 28 and will be held in the openings 28 by means of spring 29. This will lock the handles 25 against movement around the axis of the bolt 20. The sections 10 and 11, and possibly the section 31, will thus be rigidly held together to form a boat structure. This structure may be used as a row-boat or it may be used as an outboard motor boat.

It will thus be seen that the boat here disclosed is combined of sections which are light in weight and possess considerable strength, and which may be easily assembled together to form a boat structure as desired.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. A sectional boat including primary and secondary sections, each such section having a bottom, side walls, a relatively thin transverse bulkhead, said bulkheads closing the contiguous ends of said sections, and a horizontal seat member which is united along one edge thereof with the upper edge of said bulkhead and at its ends with said side walls, said seat members uniting, when said boat is assembled, to form a seat; a pair of vertical bosses united with the bottom, bulkhead, and seat member of said primary section and disposed inside said section, there being bores extending vertically through said bosses at the upper and lower ends of which bores lug receiving

recesses are formed in the bulkhead, bosses, bottom, and seat member of said primary section; upper and lower locking lugs provided on the bulkhead of said secondary section which fit into said recesses when said sections are juxtaposed in assembling said boat, said lugs having vertical holes which are thereby aligned with said bores; bolts which extend upwardly when in use through said holes and said bores; and nuts which are applied to the threaded upper ends of said bolts to complete the assembly of said boat, there being recesses formed in said upper lugs in which said nuts are entirely received downwardly when so applied.

2. A combination as in claim 1 in which pivot forks are mounted on the said nuts; and handles pivoted on said forks and adapted to be swung about their pivots into horizontal position after their use in tightening said nuts on said bolts.

3. A combination as in claim 1 in which pivot forks are mounted on the said nuts; handles pivoted on said forks and adapted to be swung about their pivots into horizontal position, after their use in tightening said nuts on said bolts; and means for locking said handles against rotation about the axes of said bolts when said handles are swung into horizontal position.

WILLIAM J. EVERETT.
